(57) **CLAIM**

We claim the ornamental design for a product display stand,
as shown and described.

DESCRIPTION

FIG. 1 is a top perspective view of a product display stand
of the present invention;

FIG. 2 is front elevation view thereof;

FIG. 3; is a right side elevation view thereof, where the right
side elevation view is a mirror image of the left side
elevation view;

FIG. 4 is a rear elevation view thereof;

FIG. 5 is a top plan view thereof;

FIG. 6 is a top perspective view of a product display stand
as shown in FIGS. 1-5 in an embodiment arranged side-by-
side immediately adjacent another product display stand;
FIG. 7 is a top perspective view of a product display stand
as shown in FIGS. 1-5 in an embodiment arranged with two
or more immediately adjacent, side-by-side product display
stands;

FIG. 8 is a top perspective view of a product display stand
as shown in FIGS. 1-5 in an embodiment arranged imme-
diately adjacent in a vertical stack with another product
display stand;

FIG. 9 is a top perspective view of a product display stand
as shown in FIGS. 1-5 in an embodiment arranged imme-
diately adjacent in a vertical stack with two or more product
display stands;

FIG. 10 is a top perspective view of a product display stand
as shown in FIGS. 1-5 in an embodiment arranged imme-
diately adjacent in a staggered stack with another product
display stand; and,

FIG. 11 is a top perspective view of a product display stand
as shown in FIGS. 1-5 in an embodiment arranged imme-
diately adjacent in a staggered stack with two or more product
display stands.

The broken lines shown in the drawings are included for the
purpose of illustrating environment and form no part of the
claimed design. The break lines shown in FIGS. 7, 9, and 11
are not part of the claimed design and represent that no
particular length is claimed.
